WELL POINT

William W. Lee, Maywood, Ill.

Application February 18, 1935, Serial No. 7,001

7 Claims. (Cl. 166—5)

Well points may be driven down into the soil by means of blows delivered upon the upper ends of the same or extensions thereof or by drilling holes hydraulically in advance of the points and permitting the points to descend into the holes as the drilling progresses.

The object of the present invention is to provide a well point of any usual or suitable construction with simple and novel means to enable it rapidly and efficiently to drill into the soil, ahead of the point, upon forcing fluid under pressure down through the same.

The various features of novelty whereby my invention is characterized will hereinafter be pointed out with particularity in the claims; but, for a full understanding of my invention and of its objects and advantages, reference may be had to the following detailed description taken in connection with the accompanying drawing, 20 wherein:

Figure 1 is an elevation of a well point, one of the coupling elements being shown in section; Fig. 2 is a central longitudinal section, on a larger scale, through the lower end of the point, 25 the parts being in the relative positions assumed during a drilling operation; Fig. 3 is a view similar to Fig. 2, showing not quite the same fragment as does Fig. 2, the parts being in the relative positions occupied during the times water is being drawn up through the point and which are also the normal positions when the point is idle; Fig. 4 is a section on line 4—4 of Fig. 3, the wire mesh and perforated sheet metal sheathing which are shown in Fig. 2 being omitted from 30 this view as is also the case with respect to Fig. 3; and Fig. 5 is a section on line 5—5 of Fig. 3.

The well point as a whole, aside from the improved jetting means, may take any usual or preferred form since the present invention is not concerned with the details thereof. In the arrangement shown, there is a soil-piercing head 1 secured to the lower end of a suitable tubular strainer element. The strainer element is illustrated as a piece of heavy pipe 2 screwed into the head and filled with holes 3, a wire mesh layer 4 surrounding the pipe, and a sheathing in the form of a shell or sleeve 5 of thin perforated sheet metal surrounding the whole. As shown in Fig. 1, there is a coupling or union 6 screwed upon the upper end of the pipe 2 and, fixed in this member, is a tube or conduit 7 whose external diameter is considerably smaller than the internal diameter of the pipe 2. The tube 7 is coaxial with the pipe 2 and extends down through the latter into the vicinity of the head 1. When a

partial vacuum is created in the pipe 7, through a connection with a pump or the like, while the point is immersed in water, water enters the lower end of the tube 7 and flows up through the latter. Therefore, although water may flow into the interior of the tubular strainer throughout the entire height of the latter, water is withdrawn from the bottom thereof only.

The upper half of the head 1 is bored out to a diameter sufficient to receive the pipe 2 and therefore contains a chamber 8 of considerable size. There is an axial bore 9 extending from the bottom of the chamber 8 down through the nose or tip of the head. This bore is enlarged, beginning a short distance from the lower end, to receive a short tube 10 whose internal diameter is equal to that of the lower section of the bore. The tube 10, which may be a pressed fit in the bore 9, is long enough to extend up through the chamber 8 and into the lower end of the tube 7. The tube 10 is of smaller diameter than the internal diameter of the tube 7.

Surrounding the lower end of the tube 7 is a long sleeve, 11, held against rotation therein but slideable up and down on the same within limits. In the arrangement shown, the tube 7 has therein two diametrically opposed longitudinal slots 12, and the sleeve 11 has a pair of pins projecting inwardly into these slots. The pins may conveniently be screws 13, as shown. The length of the slots determines the distance through which the sleeve 11 may move up and down. The tube 7 and the sleeve 11 have therein large side openings 14, 14 and 15, 15, respectively; the combined areas of the openings 35 in each being preferably greater than the cross-sectional area of the tube 7. These openings are so disposed that when the sleeve is lowered as far as it will go, solid or imperforate portions thereof cover the openings 14 in the tube 7 and imperforate parts of the wall of the said tube extend over the openings 15 in the sleeve, as indicated in Fig. 2; whereas, when the sleeve is moved up as far as it will go, each side opening 40 in the sleeve registers with the corresponding side opening in the tube 7, as indicated in Figs. 3 and 4. The member 11 may therefore be regarded as a sleeve valve.

The lower end of the sleeve valve, beyond the 50 lower end of the tube 7, is thickened in the inward direction, as at 16, to produce an internal diameter only a little greater than the external diameter of the short tube 10. The said thickened part is of considerable axial length so as to 55

provide a narrow annular space 17 of considerable length between the tube 10 and the thickened part of the sleeve valve.

Below the sleeve valve, and surrounding the tube 10 within the chamber 8, is a compression spring 18 which tends constantly to hold the valve in its raised position. When water or other fluid under pressure is forced down through the tube 7 and reaches the tube 10, some enters the tube 10 and some passes down around the outside of the latter until it reaches the internal annular shoulder on the sleeve produced by the thickened part 16. A little of the fluid escapes down through the annular passage 17, but the pressure of the remainder on the said shoulder drives the valve down, against the resistance of the spring, into the position shown in Fig. 2. Thereafter, as long as the downward flow of fluid under pressure is maintained, the valve will be held down by the pressure of the fluid; and, because the side openings in the valve and the tube 7 are closed, the only outlets for the fluid are through the jetting passage 9 in the head and through the little annular passage around the tube 10 into the chamber 8 in the head. Much the larger part of the fluid travels down through the jetting passage and drills or dredges out the soil below the head to permit the point to descend. The smaller stream, which is discharged into the chamber 30 in the head, flows out through the strainer and acts in the manner of a lubricant to reduce the friction between the point and the surrounding soil.

It will be seen that by discharging a powerful jet straight down at the top of the device, the hole into which the well point descends may be driven very accurately as to direction and without requiring more material to be dredged out than is necessary to make a hole of just the proper size. The work of driving a well point may therefore be done rapidly, accurately, and with a minimum expenditure of power or energy.

As soon as the downward pressure of the jetting fluid stops, the spring lifts the sleeve valve and places the interior of the lower end of the tube 7 in open communication with the surrounding space within the strainer. Then, upon producing a suction in the tube 7, water will be drawn in from the lower end of the chamber within the strainer, through the registering openings 15 and 14, and up through the tube 7. The strainer has an effective water inlet area extending entirely around the same and from top to bottom; and, because the strainer element is usually several feet long, such effective inlet area is many times that of the cross-sectional area of the tube 7 and still larger in proportion to the cross-sectional area of the jetting passage in the head. Consequently, water will not be drawn up through the jetting passage in the head but will be taken from the supply that seeps in through the wall of the strainer. If it be desired to provide a positive closure of the jetting passage except while jetting, a suitable upwardly seating check valve device may of course be arranged in the head in association with the jetting passage.

I have found that sometimes there is a tendency to build up a back pressure below the sleeve valve during jetting and thereby cause the valve to rise and permit the fluid under pressure to flow out laterally through the side openings 14 and 15. In order to prevent this I place within the chamber in the head a cylindrical shell 19, surrounding and coaxial with the tube 10, this

shell bottoming on the bottom wall of the said chamber and terminating at the top at such a level that the lower end of the sleeve valve will touch the upper edge of the shell when the valve is at the lower limit of its movement. The outer 5 diameter of the shell is preferably at least as great as the corresponding diameter of the valve. The shell may be in the form of a cup, as shown, the bottom wall of which has a central opening just large enough to permit it to be pressed down 10 over the tube 10 and be frictionally held thereby against accidental displacement. The shell 19, or the cylindrical wall thereof if the shell be cup-shaped, has large openings or windows 20 therein at a short distance above the lower end. 15 The water that escapes down through the annular passage 17, around the tube 10, during jetting, flows out through the openings 20 and up in the free space within the strainer around the central pipes or tubes and the sleeve valve, and 20 escapes through the perforations in the strainer. I do not know whether it is due to a kind of injector action that the water in the shell 19 fails to exert any lifting effort on the sleeve valve 11; but, at any rate, the presence of the shell 25 prevents the happening of the objectionable lifting of the valve at times when it should remain down.

It will thus be seen that a well point constructed in accordance with my invention may 30 be like any ordinary well point having a central suction pipe extending down into the vicinity of the lower end of the strainer element, except that the head has a jetting passage, that there is on said central pipe a sliding sleeve valve and 35 that there are at most two little pieces of extra tubing fixed in the head; so that the cost of a well point containing my improvements, over that of an ordinary well point, is very small. Also, because there is only a single movable part, 40 the sleeve valve which is housed in and protected by the body of the well point, the device is sturdy and rugged and in no greater danger of being damaged or worn than is the simpler type of 45 non-jetting well point.

While I have illustrated and described with particularity only a single preferred form of my invention, I do not desire to be limited to the exact structural details illustrated and described; but intend to cover all forms and arrangements 50 which come within the definitions of my invention constituting the appended claims.

I claim:

1. In a device of the character described, a tubular strainer element having at the lower end 55 a soil-piercing head provided with a jetting passage, a tube within and extending lengthwise through the strainer element to and in open communication with said passage, said tube having a large side opening near the lower end, and 60 means including a sleeve slidable on said tube to close said opening when fluid is forced down through the tube and to uncover the opening when fluid is drawn up through the tube.

2. In a device of the character described, a 65 tubular strainer element having at the lower end a soil-piercing head provided with a jetting passage, a short tube forming the inner end of said passage, a long tube of larger diameter than the short tube extending up through said strainer 70 element in alignment with the short tube, a sleeve mounted on the lower end of the long tube and telescoped upon the upper end of the short tube, said sleeve having at the lower end an internal annular flange surrounding the short 75

tube, there being side openings in the sleeve and the long tube which register when the sleeve is moved up and are brought out of registration when the sleeve is moved down, and a spring tending to hold the sleeve up.

5. 3. The combination with a device comprising a tubular strainer element having at its lower end a soil-piercing head provided with a jetting passage, together with a conduit larger in diameter than said passage extending lengthwise through said strainer element to said passage, of means including a spring and an element engaged with said spring and subjected to a differential pressure due to the difference between the diameters 10 of said passage and said conduit automatically to shut off communication between the interior of the conduit and the surrounding space in the strainer element when fluid under pressure is flowing down through said conduit and automatically to establish such communication at all 15 other times.

4. In a device of the character described, a tubular strainer element having at the lower end a soil-piercing head provided with a jetting passage, a tube within and extending lengthwise through the strainer element to said passage, said tube having a large side opening near the lower end, and means including a sleeve slideable on and having a contracted portion beyond the lower end 20 of said tube to close said opening when fluid is forced down through the tube and to uncover the opening when fluid is drawn up through the tube.

5. In a device of the character described, a tubular strainer element having at the lower end a soil-piercing head provided with a jetting passage, a short tube forming the inner end of said passage, a long tube of larger internal diameter than the external diameter of the short tube extending up through said strainer element 25 in alignment with the short tube, a sleeve mounted on the lower end of the long tube and extending downward from the same around the short tube, the lower end of the sleeve being contracted to an internal diameter only slightly 30 greater than the external diameter of the short

tube, there being side openings in the sleeve and the long tube which register when the sleeve is moved up and are brought out of registration when the sleeve is moved down, and a spring tending to hold the sleeve up.

5

6. In a device of the character described, a tubular strainer element having at the lower end a soil-piercing head provided with a jetting passage, a short tube forming the inner end of said passage, a tube smaller in diameter than the 10 strainer element and larger in diameter than said short tube extending lengthwise through the latter and surrounding the upper end of the short tube, a sleeve valve on the lower end of the long tube projecting down below the latter and 15 contracted at its lower end to produce between the same and the short tube a very narrow annular passage, the sleeve valve and the long tube having large side openings which register when the valve is raised and are covered when the 20 valve is lowered, a spring tending constantly to raise the valve, and a shell longer than and surrounding the short tube, the shell terminating at an upper level such that the sleeve valve contacts with the upper end thereof when lowered, 25 and there being outlet ports in the lower end of the shell leading into the space within the device around the shell.

7. In a device of the character described, a tubular strainer element having at the lower end a soil-piercing head provided with a jetting passage, a tube of larger internal diameter than said passage within and extending lengthwise through the strainer element to and in open communication with said passage, said tube having a large side opening near the lower end, a sleeve valve on said tube to control said opening, said sleeve valve having an annular internal shoulder forming a closure for the lower end thereof, said shoulder surrounding said passage 40 and being subjected to the pressure of jetting fluid flowing down through said tube and into said passage.
